BY Victor J. Evans

ATTORNEY

UNITED STATES PATENT OFFICE.

CLARENCE B. DAVIDSON, OF UNIONVILLE, MISSOURI.

ADVERTISING DEVICE AND MATCH HOLDER.

Application filed December 13, 1924. Serial No. 755,723.

To all whom it may concern:

Be it known that I, CLARENCE B. DAVIDSON, a citizen of the United States, residing at Unionville, in the county of Putnam and 5 State of Missouri, have invented new and useful Improvements in Advertising Devices and Match Holders, of which the following is a specification.

The object of this invention is to provide 10 a cheaply constructed but strong and durable pocket match safe which is also designed for employment as an advertising medium.

A further object is to produce a pocket match safe comprising a flexible cover having 15 one of its ends designed to be received beneath the other end when in folded condition, said cover having fixed in one of its ends a match holder whose outer portion is formed of a continuous strip, the ends of 20 which being connected to centrally disposed plates or strips, corrugated strips being arranged between the plates and the sides of the strips, and the space between the confronting faces of the plates providing a 25 pocket for a partition upon which is imprinted advertising matter, the pockets provided between the corrugated strips serving for the reception of the non-headed ends of matches.

30 To the attainment of the foregoing and other objects which will present themselves as the nature of the invention is better understood, reference is to be had to the drawing which accompanies and which forms 35 part of this application.

In the drawing:—

Figure 1 is a perspective view of the improvement.

Figure 2 is a sectional view on the line 40 2—2 of Figure 1.

Figure 3 is a sectional view approximately on the line 3—3 of Figure 2.

Figure 4 is a perspective view of the match holder.

45 The cover of my improvement may be made of any desirable material, such as cardboard or metal. The cover is formed from a single strip of material and is bent upon itself to provide a back 1, a top 2, a front flap 3 extending from the top, a bottom 4 and a front flap 5 extending from the

bottom. The front section 5 is of a materially less length than the front section 3 and when the cover is folded in rectangular shape, the end of the front section 3 is designed to be received beneath the end of the shorter front section 5, and the pressure between these lapping ends is sufficient to hold the same associated. This pressure is occasioned by means which will presently be 60 described.

In the pocket provided between the short front section 5, the bottom 4 and the back 1 there is received the match holder which is illustrated in detail in Figure 4 of the drawing. 65 The match holder comprises an outer strip of suitable material which has its ends rounded and its free edges disposed inlapping relation and connected together. This provides a substantially rectangular casing 70 6. Arranged centrally in the casing and connected to the rounded ends thereof there are spaced plates 7 and 8. The plates are closely related and are designed to receive therebetween a division plate or strip 9. 75 The strip 9 has on its outer face advertising indicia, as has also the front 3 and if necessary the back of the device. The front 3 is really in the nature of a flap and will for convenience be hereinafter so termed. 80

In the compartments provided between the outer faces of the plates 7 and 8 and the sides of the casing 6 there are arranged corrugated strips 10, the corrugations in the said strips providing pockets for the non-headed ends of match stems 11. Preferably, and as disclosed in Figures 1 and 3 of the drawing, the casing 6 and the elements carried thereby are retained in the cover through the medium of a staple 12 but, of course, other means may be provided for this purpose. The front 6, above the staple has arranged thereon a match striking surface.

95 The flap 3 has its free end received beneath the front section 5 when the device is in closed position. The plates 7 and 8 may be constructed of paper, cardboard, metal or other desired material. The matches may have their stems of wood or paraffined paper, and may be adhesively sustained in the pockets provided therefor. 100

Having described the invention, I claim:—

As a new article of manufacture, a match safe comprising a cover made from a single strip of material bent upon itself to provide a spaced back and front, one portion of the front being of a greater length than the other and providing a flap, a casing secured

between the front and back of the cover at the lower end thereof, spaced longitudinal 10 plates in the casing, corrugated sheets between the plates and the sides of the casing, and said plates designed to receive therebetween a division strip.

In testimony whereof I affix my signature.
CLARENCE B. DAVIDSON.
